PLIER TYPE IMPLEMENT

Herbert W. Marano, Brooklyn, N. Y., assignor to
 Wilson-Jones Company, Chicago, Ill., a corpora-
 tion of Massachusetts

Application December 5, 1952, Serial No. 324,338

2 Claims. (Cl. 81—43)

1

The present invention relates generally to manually operable tools, and in particular it relates to tools of the plier type, having a pair of handle elements to be urged towards each other for actuation of the operating components on the tool.

The main object of the present invention is to provide an improved manually operable tool comprising a pair of opposing and normally divergent members, a handle for each member operating about a double pivot to urge the diverging members towards each other, and means to lock the handles onto the members and in operative relation thereto.

Still another object of the present invention is to provide a lock member for a pair of normally divergent members having cooperating tool elements at the ends thereof and for a pair of manually operable handles for said divergent members, said lock member being easily removable.

Still another object of the present invention is the provision of a lock member for a pair of normally divergent tool members and handles therefor, said lock maintaining the handles in position to actuate the tool members and providing a bearing for pivoting the handles.

Still another object of the present invention is the provision of a manually operable tool comprising a pair of cooperative tool element bearing members, a handle for each thereof, and a lock member, the handles having double pivots one of which is adjacent the lock member and the other of which is adjacent one of the divergent members.

Other, further and more specific objects of the present invention will, in part, be pointed out hereinafter and, in part, be apparent from the following description of several illustrative embodiments.

In the drawings annexed hereto, and forming a part hereof,

Figure 1 is a side elevational view, partly in section, of one form of device constructed according to and embodying the present invention;

Figure 2 is a top plan view of the front portion thereof;

Figure 3 is a plan view, partly in section, on the line 3—3 of Figure 1;

Figure 4 is a front elevational view, partly in section, along the line 4—4 of Figure 1;

Figure 5 is a side elevational view, partly in section, of another form of device constructed according to and embodying the present invention;

2

Figure 6 is a plan view, partly in section, on the line 6—6 of Figure 5; and

Figure 7 is a side elevational view of still another form of device constructed according to and embodying the present invention.

The devices according to the present invention are characterized by a pair of elongated members secured together at an end thereof and normally divergent at their other and opposing ends, said other ends being provided with cooperative tool elements, a manually operable handle for each element, and a lock member to maintain the handles in operative position on the divergent members, the lock passing through aligned slots in the divergent members and in the handles and including components extending over the handle ends whereby to provide a bearing about which an upper portion of each handle can pivot, each handle having a lower portion resting against and pivoting about one of the resilient members.

In Figures 1 to 4, I have illustrated the application of my invention to a hand tool for removing staples or the like, the device being indicated generally by reference numeral 10 and comprising a pair of opposing members 12, 14 of substantially similar length. These members 12, 14 may be die-stamped or punched of springy, preferably metallic material, flattened at the rear thereof, as at 16, 18 respectively, and riveted together as at 20. Members 12, 14 are bent outwardly and then forwardly, as at 22, 24 respectively spaced forwardly of the riveted ends 16, 18, to offset with respect to each other the bodies and front ends thereof, as shown in Figure 1. The permanent deformations of members 12, 14 at 22, 24 cause the unattached ends thereof to spread apart; the inherent springiness of the material permitting flexion at the bend areas. The front end 26 of member 12 is provided with a downwardly extended tooth portion 28, and the front end 30 of member 14 is provided with a forwardly extended lip 32, which cooperates with tooth 28 for removal of clinched staples or the like, when the members 12, 14 are brought together to cause tooth 28 to ride over, against and past lip 32, as will be readily understood.

A longitudinally extending slot 34 is formed in member 12, midway between the sides thereof, and a similarly sized, shaped and positioned slot 36 is formed in member 14, also midway between the sides thereof, the said slots 34, 36 being vertically aligned. The sides of members 12, 14, from a point rearward of the rear ends of slots 34, 36, are flanged upwardly and downwardly respectively, as indicated at 38, 40 respectively,

3

to impart strength and rigidity to said members 12, 14.

In order to operate the device manually, I provide a pair of actuating handles 42, 42, roughly U-shaped in section. The depending side walls 44, 44 of each handle merge at the rear end 46 thereof, for easier manipulation. A longitudinal slot 48 is formed in and adjacent the forward end 50 of each handle, spaced rearwardly of the handle end 50, thereby providing a cross-bar 52 as an integral part of the handle, this cross-bar 52 defining an upper pivot. The depending walls 44, 44 immediately adjacent the forward end 50 of each handle 42, are so shaped that their lower edges define cam surfaces or lower pivot portions 54. The lower pivot portions 54, 54 are defined by the lines or areas of intersection of the bottom edges 56 of depending walls 44, 44 which angle upwardly at the forward ends of the handles from a point rearward of cross-bar 52, and the bottom edges 58, 58 of the side walls, which form an inner angle with edges 56 of somewhat less than 180°.

In order to lock actuating handles 42, 42 in operating position in the device, and in order to provide bearing surfaces for the upper pivot portions constituted by cross-bars 52, 52, I provide a bracket or locking member 60. Bracket 60 is formed of substantially flat, rigid material having a body portion 62 and a pair of arms 64, 64 extending forwardly and outwardly from the top and bottom of body 62, each arm terminating in an inwardly directed finger 66, defining a recess 68 between the arm 64 and the finger 66, each recess 68 defining a bearing for the cross-bars or upper pivots 52, 52. The lower portion 70 of body 62 at the rear thereof is provided with a rearwardly extending heel 72.

As seen in Figure 1, slots 34, 36 are slightly longer than the width of bracket 60 across the lower portion 70 thereof; the upper portion 74 of bracket body 62 being appreciably narrower than slots 34, 36 are long.

In assembled condition, the locking member or bracket 60 registers with slots 34, 36 in members 12, 14 and the bracket arms 64, 64 extend through the said slots therein and through slots 48, 48 in handles 42, 42. The pivots or cross-bars 52, 52 rest in the bearing recesses 68, 68, being urged and retained therein by the outward pressure of the resilient members 12, 14, bearing against the lower edge walls 56, 56 of the handle members and the pivot portions 54, 54. The inwardly directed fingers 66, 66 fit over the cross-bars 52, 52 and extend into the hollow of the handle at the front thereof.

In order to assemble the device described hereinabove, members 12, 14 are first provided with the coacting elements 28, 32 at the forward ends thereof and then riveted together at the flattened rear ends 16, 18 thereof, as at 20, 29. The arm 64 extending from the narrower portion 74 of bracket 60 is then inserted from below the lower member 14 through slot 36 therein, thence through slot 34 in the upper member 12, and then turned counterclockwise until the fingers 66, 66 rest respectively on the outer surfaces of said members 12, 14, retained therein by the normal spring divergence of said members 12, 14. Thereupon the forward ends 26, 30 of members 12, 14 are manually pressed together, leaving a space between arms 64, 64 and members 12, 14, whereupon the handles 42 may be slid rearwardly on the outer surfaces of said members 12, 14 from the forward ends 26, 30 thereof so that the

75 fingers 66 and the ends of the arms 64, 64 pass through slots 48, 48 until the cross-bars 52, 52 are aligned with the bearing recesses 68, 68, whereupon the compressed ends 26, 30 of the members 12, 14 are released to spring outwardly and away from each other into the position of Figures 1 and 2, thereby locking the handles on the device in fully operative position.

When it is desired to actuate the device of the 10 present invention as a staple remover, extension 32 and tooth 28 are aligned with the staple to be removed, and as handles 42, 42 are manually pressed towards each other, the leading edge of the tapered tooth 28 will first enter beneath the 15 staple body and then, as movement of tooth 28 toward extension 32 continues in response to handle pressure, the clinched staple will be flared open, so as to render it easily removable from the material into which it had been clinched. The 20 normal divergent biasing of members 12, 14 urges the upper pivots or cross-bars 52, 52 into tight engagement with the bearings or recesses 68, 68, retaining them there and locking the parts in 25 assembled condition during this manipulation of the device. As the pressure on handles 42, 42 begins, they swing about their upper pivots or cross-bars 52, 52 in recesses 68, 68, and the lower pivots 54, 54 of the handles bearing against the 30 upper and outer faces of the resilient members 12, 14 force them towards each other to complete the operation above described.

In Figures 5 and 6, I have illustrated my invention as applied to a hole punching tool, this embodiment differing only in a change in the 35 character of tool provided on the opposing ends of members 12, 14 and in the provision of, for example, a stripper and a stop bar. Parts in the modification of Figures 5 and 6 similar to parts in the modification of Figures 1 to 4 have been given similar reference numerals, since their 40 structure and operation are substantially similar.

Thus, in the hole punching implement illustrated in Figures 5 and 6, the sides of both members 12, 14 forwardly of the bend areas 22, 24 are 45 flanged outwardly around the sides and at the front as at 38, 40; and the upper member 12 is provided with a cylindrical punch element 90 depending from the underside thereof, rearwardly of the front end 26 thereof, and the lower element 14 is apertured as at 92, in registry with 50 punch 90. Interposed between members 12, 14 is a stripper bar 94, secured by the rivets 20, and apertured near the front thereof as at 96 in registry with punch 90, to permit passage therethrough of the punch element 90. Stripper 94 is 55 slotted longitudinally thereof as at 98, the rear portion of which is in line with the slots 34, 36 in members 12, 14. A cross-bar 99 is provided across the forward end of slot 98, forming a 60 smaller opening 102 at the front thereof. A strip 100 is punched out of the body of member 14 and bent upwardly, of such length as to serve as a stop to limit movement of members 12, 14 towards each other, the aperture 102 in stripper 94 permitting passage of stop 100 therethrough. 65 As illustrated in Figure 5, stripper 94 is no longer than members 12, 14 and its front end 95 extends slightly forwardly of the front ends 26, 30 of members 12, 14 and is curved upwardly to guide the material being perforated between the coacting 70 jaw front ends of the instrument. The forward edge 11 of lock member 62 is provided with a notched projection 73, into which cross-bar 99 fits to maintain the stripper centrally located 75 between the upper and lower members 12, 14.

In the modification of Figure 7, the invention is applied to a simple pair of pliers, the coacting spring-members being provided, at their forward ends, with inwardly directed, opposing toothed jaws 28a and 30a. Application of pressure on handles 42, 42 causes movement of jaws 28a, 30a towards each other to grip and hold any object disposed therebetween.

As will be readily appreciated, the present invention may be embodied in mechanisms formed of any suitable material, preferably, for the most part, stamped or otherwise formed of sheet metal such as steel. Furthermore, by the provision of the locking member, a pair of coacting elements may be mounted in opposing relationship, to operate positively, easily and efficiently.

The various mechanisms may be assembled and disassembled easily and quickly, without requiring the services of particularly skilled workers, for shipping, storage and the like. While several specific applications of the present invention have been shown and described hereinabove, it will be clear that other applications may be achieved within the scope of the present disclosure, and my invention is to be limited only by the scope of the appended claims.

The opposing members, secured at one end of each thereof and normally divergent at the other ends thereof, the handles and the locking member are simple and easy to make and assemble. The forwardly extended arms on the lock members, and the bearing therein, in combination with the upper and lower pivots on the handles about the bearings and resilient members respectively provide positive and direct application of pressure to the particular operating elements mounted at the free ends of the opposing members.

Having described the present invention, what I claim and desire to secure by Letters Patent is:

1. A manually operable hand tool comprising a bifurcated member including a pair of forwardly directed divergent arms resiliently joined at their rear by a crotch portion and having opposite openings formed in said arms closely adjacent to said crotch portion and having a tool element disposed adjacent the forward ends of said arms, a substantially U-shaped locking member including a pair of forwardly directed arms joined by a cross-piece passing through said opposing openings, said locking member arms extending longitudinally along the outer faces of said bifurcated member arms and terminating in inwardly directed fingers, and a pair of rearwardly directed divergent handles, each of said handles having an aperture formed adjacent its forward end engaged by a corresponding locking member arm and having an inner cam surface engaging the confronting surface of the corresponding bifurcated member arm.
2. A manually operable hand tool in accordance with claim 1, wherein each of said handles is provided with a cross-piece disposed between the aperture formed therein and the forward end thereof, said cross-piece registering with the crotches defined by the joint between said locking member arms and said inwardly directed fingers.
